UNITED STATES PATENT OFFICE.

JACOB MAYO LENZ, OF CHICAGO, ILLINOIS, ASSIGNOR TO RUNZEL-LENZ ELECTRIC MANUFACTURING COMPANY, OF CHICAGO, ILLINOIS, A CORPORATION OF ILLINOIS.

INSULATED TERMINAL.

Application filed April 3, 1924. Serial No. 703,967.

My invention relates to insulated terminals for conductors and more particularly to insulated terminals for conductors used in cords for telephone receivers.

5 Ordinarily the terminals on a conductor used in a telephone receiver cord are not protected by any insulating material. Accordingly, in certain types of apparatus a short circuit often occurs between the body portion of the terminal and some part of the telephone apparatus adjacent thereto, which is very undesirable particularly when used in connection with radio apparatus.

10 While numerous types of connecting terminals are provided on the end of conductor cords of this character, all of these embody a contact making portion and a body or shank portion.

15 It is a purpose of my invention to insulate the body or shank portion of the terminal from the rear portion of the same to a point spaced from the free end thereof to leave the free end portion exposed to serve as a contact member.

20 More particularly it is the purpose of my invention to provide an insulating covering for all of a contact terminal provided on the end of a conductor except the portion thereof that actually serves to make contact, said insulating covering being preferably in the form of a sheath extending from the insulation on the conductor to the contact making portion of the terminal. Said sheath is preferably made of braided material and the braiding preferably begins at 25 a point on the insulating covering of the conductor rearwardly of the terminal and extends over the terminal to a point adjacent the contact making portion thereof. Then the braiding is preferably lapped back 30 on itself to form a double sheathing over the terminal, the outer layer of said braiding extending over the free end portion of the braiding where the braiding was begun and extends an appreciable distance rearwardly 35 thereof to firmly bind the free end of the braiding in position.

40 It is still a further purpose of the invention to provide a conductor cord that has a pair of conductors therein and which is provided with free end portions, each containing a conductor with terminals, each having a braiding extending over all but the contact end thereof, said braiding being lapped back in the manner referred to above so as to

provide a double layer of braiding over the terminal and said braiding extending rearwardly over the insulating covering on the conductors to the joint where the conductors enter the portion of the cord containing the pair of conductors. One of said braiding ends slightly beyond said joint and the other of said braidings forms a sheath around both said conductors to hold the same in paired relationship and embracing said first sheathing at the free end thereof to firmly secure said free end in position.

45 It is still another object of the invention to provide terminals that have reduced portions and enlarged portions so as to provide an irregular surface lengthwise thereof in combination with the above mentioned braiding so that said braiding is held from movement lengthwise of said terminals.

50 Other objects and advantages of the invention will appear as the description of the accompanying drawings proceeds. However, I desire to have it distinctly understood that I do not intend to limit myself to the exact details shown or described but that I 55 intend to include as part of my invention all such obvious changes and modifications of parts as would occur to a person skilled in this art and as would fall within the scope of the claims.

In the drawings:

55 Fig. 1 is a fragmentary, elevational view of a portion of the cord embodying my invention; and

60 Fig. 2 is a longitudinal, sectional view of the end portion of a cord embodying my invention.

65 Referring in detail to the drawings, the conductor cord comprises an end portion having a pair of conductors 3 and 4 therein, 70 said conductors being each covered with any suitable insulating covering, preferably a braided covering, such as indicated in the drawings. The end portion of each of said conductors is bared as is customary and suitable connecting terminals 5 are secured thereto. Said terminals 5 comprise, preferably, a loop portion 6 having an opening 7 75 therein, as is customary, and a shank portion 8. The shank portion 8 is preferably integral with the loop portion and the entire terminal is preferably made of sheet metal.

80 The shank portion 8 comprises a pair of fingers 9 and 10 that are clamped around the insulating covering on the end of the 85

cords 3 and 4 adjacent the bare part thereof and a sleeve portion 11 is provided on each of said members embracing the bare end of the conductor. The conductor is ordinarily 5 wound with a binding wire 12 which is exposed between the sleeve 11 and the fingers 9 and 10. The fingers 9 and 10, of course, also form substantially a sleevelike portion. Thus, the terminal is provided with portions 10 of greater diameter at the sleeve 11 and at the fingers 9 and 10.

In the form of terminal shown the eye portion is the portion that engages the co-operating terminal to make the contact and 15 the shank portion is preferably in many cases insulated so that it can not accidentally make contact with any part adjacent thereto. In order to accomplish this purpose I provide an insulating covering comprising a 20 braiding which begins at the free end portion 13 thereof surrounding the insulating covering on the conductors 3 and 4 and which is braided from this point outwardly on the shank portion of the terminal to substantially 25 the contact portion of the terminal at which point it is turned or lapped back, as indicated at 14, to thus form an inner ply 15 and an outer ply 16 of braided material over the shank portion of the terminal. The outer ply 16 extends rearwardly 30 over the free end portions 13 to hold the free end portions in position. Then said outer plies continue as a single ply on the conductors 3 and 4, the ply on the conductor 3 being indicated by the numeral 17 and the 35 ply on the conductor 4 by the numeral 18 to distinguish between the two for a purpose which will be evident as the description proceeds.

40 The braiding 17 extends along the conductor 3 and terminates at the free end portion 19, while the braiding 18 extends over the conductor 4 until the conductor 3 is paired therewith at which point the braiding is widened to include the conductor 3 as well 45 as the conductor 4, as indicated at 20. The braiding 18 then continues as an outer sheath over the pair of conductors 3 and 4 to hold the same in paired relationship, as 50 will be clear from Fig. 1 and Fig. 2, and extends over the braiding 17 at the free end 19 thereof to bind said free end firmly in position and cover the same.

55 Due to the provision of the recesses or cut away portions of the terminals between the sleeve 11 and the fingers 9 and 10, the braiding will be slightly necked in, as indicated at 21. As the braiding is done directly on the terminal by means of a suitable braiding machine and as the threads from which the braiding is made are under tension, this necked in portion will firmly bind the sheath 60 to the terminals and prevent longitudinal movement of the terminal relative to the sheath.

Having thus described my invention what I desire to claim and secure by United States Letters Patent is:

1. In a device of the character described, a pair of conductors each having an insulating covering thereon, a terminal on each of said conductors, said terminals each having a sheath of insulating material and an exposed end portion serving as a contact, 70 said sheaths extending rearwardly from said terminals over said insulating covering, one of said sheaths embracing both said conductors at a point spaced from said terminals and the other of said sheaths terminating on its conductor under said first sheath to 75 bind the free end thereof in position.

2. In a device of the character described, a pair of conductors each having an insulating covering thereon, a terminal on each of said conductors, said terminals each having 85 a sheath of braided insulating material and an exposed end portion serving as a contact, said sheaths extending rearwardly from said terminals over said insulating covering, one of said sheaths embracing both said conductors at a point spaced from said terminals and the other of said sheaths terminating on its conductor under said first sheath to 90 bind the free end thereof in position.

3. In a device of the character described, 95 a pair of conductors each having an insulating covering thereon, a terminal on each of said conductors, said terminals each having a sheath of insulating material and an exposed end portion serving as a contact, 100 said sheaths each having a two-ply portion covering said terminal and having a single ply extending rearwardly from said terminals over said insulating cover, one of said sheaths embracing both said conductors at 105 a point spaced from said terminals and the other of said sheaths terminating on its conductor under said first sheath to bind the free end thereof in position.

4. In a device of the character described, 110 a pair of conductors each having an insulating covering thereon, a terminal on each of said conductors, said terminals each having a sheath of insulating material and an exposed end portion serving as a contact, said 115 sheaths each comprising an inner ply extending from a point on its conductor rearwardly of said terminal to a point short of the end of said terminal and a second ply continuous with said first ply extending rearwardly from said terminals over said insulating covering, one of said sheaths embracing both said conductors at a point spaced from said terminals and the other of said sheaths terminating on its conductor under 120 said first sheath to bind the free end thereof in position.

5. In a device of the character described, 125 a pair of conductors each having an insulating covering thereon, a terminal on each of 130

- said conductors, said terminals each having a sheath of braided insulating material and an exposed end portion serving as a contact, said sheaths each comprising an inner ply 5 extending from a point on its conductor rearwardly of said terminal to a point short of the end of said terminal and a second ply continuous with said first ply extending rearwardly from said terminals over said insulating covering, one of said sheaths embracing both said conductors at a point spaced from said terminals and the other of said sheaths terminating on its conductor under said first sheath to bind the free end thereof 10 15 in position.
6. In a device of the character described a conductor, a terminal having a shank embracing said conductor and a braided insulating sheath having a single layer covering 20 said conductor and two layers integral with said single layer covering said shank, said shank having a portion of reduced circumference and said two layers of said sheath having portions of reduced circumference engaging said reduced shank portion. 25
7. In a device of the character described, a conductor having a terminal thereon, said terminal having a shank embracing said conductor and a braided insulating sheath covering the shank portion of said terminal and 30 extending beyond said shank portion on said conductor, said shank having a reduced portion between the ends thereof and said insulating sheath having a portion of restricted diameter seated in said reduced portion 35 to hold said sheath from longitudinal movement on said terminal.

In witness whereof, I hereunto subscribe my name this 14th day of March, A. D. 1924.

JACOB MAYO LENZ.
